FIGURINE FOR ARITHMETIC INSTRUCTION

Charles E. Jones, Evanston, Robert H. Crowle, Mount Prospect, and William G. Crowle, Deerfield, Ill., assignors of one-half to Science Research Associates Inc., Chicago, Ill., a corporation of Delaware, and one-half to Western Publishing Company, Inc., Chicago, Ill., a corporation of Wisconsin

Filed Apr. 29, 1963, Ser. No. 74,648

Term of patent 14 years

(Cl. D25—1)

FIG. 1

FIG. 2

FIGURE 1 is a front elevational view of a figurine for arithmetic instruction showing my new design;

FIGURE 2 is a top plan view thereof;

FIGURE 3 is a rear view in elevation thereof;

FIGURE 4 is a side view thereof; and

FIGURE 5 is an enlarged sectional view taken along the line 5-5 of FIGURE 3.

The support shown in broken lines in FIGURES 1, 2, 3 and 4 is for purposes of illustration only.

We claim:

The ornamental design for a figurine for arithmetic instruction, as shown and described.
